UNITED STATES PATENT OFFICE

KARL MAYR, OF CHICAGO, ILLINOIS, ASSIGNOR TO SIEMENS-SCHUCKERTWERKE GESELLSCHAFT MIT BESCHRANKTER HAFTUNG, OF BERLIN-SIEMENSSTADT, GERMANY

APPARATUS FOR GENERATING STEAM

Application filed June 4, 1927, Serial No. 196,508, and in Germany June 4, 1926.

My invention relates to apparatus for generating steam.

An object of this invention is to generate a large amount of steam within comparatively small space.

Another object is to provide means which make use of the high heat transfer from a radiant flame body to heating tubes to an unusually great extent.

10 Another object is to provide means for easily changing the proportion of refractory and heat-absorbing surfaces in combustion chambers.

15 Another object is to provide a design, which if used for plants of several sizes (outputs) secures the same proportion between volume of combustion chamber and heating surface capable of absorbing radiant heat for all sizes.

20 Another object is an arrangement by which easy access may be had to the burners and air supply system to the combustion chambers.

25 A further object is to provide a design in which all brickwork or refractory material which is exposed to radiant heat may either be air-cooled or cooled by the tubes carrying the operating medium.

30 It is well known that the transmission of heat by radiation has a great influence upon the economy of the operation of boilers and particularly on the first cost and for this reason the combustion chambers of nozzle furnaces (oil, gas, pulverized coal and the like) are as much as possible lined with tubes.

35 As large a heating surface as possible should be accommodated in the combustion chamber.

Only so much heat-absorbing surface can be provided in the combustion chamber that the temperature of the burning gases is reduced

40 no more but to the temperature which is required to secure complete combustion under all operating conditions.

Ordinarily one would obtain the above conditions by surrounding the combustion chamber to a greater or lesser degree by heat-absorbing tubes, through which the operating medium circulates either by natural flow (thermal system) or by artificial means (force pumps).

50 The height of the combustion chamber is

variable only to a limited extent. As the volume of the chamber is a function of the square of its diameter (for instance in the case of a cylindrical combustion chamber), and the area of its surrounding walls is—on the basis of equal height—in direct proportion to its diameter, it is obvious that the proportion of combustion chamber wall to combustion chamber volume becomes smaller with increasing size of the chamber. It may be noted in this connection that the volume of the chamber is in direct proportion to the output of the steam generator so long as the same kind of fuel is used.

In order to eliminate the difficulties which arise in dimensioning various sizes of boilers and to utilize the combustion chamber space to the best advantage, I provide besides the tubes closely surrounding the radiating space (the combustion chamber) still further tubes in the combustion chamber.

An embodiment of my invention is illustrated in the drawings attached hereto, in which—

Figure 1 shows a vertical section of my improved steam generator, and

Figure 2 a horizontal section thereof on the line 2—2 of Figure 1.

The configuration of the generator, so far as its outside shape is concerned, may have any suitable shape. It may be, for instance, round or square or octagon shape. In the present modification, a round shape is assumed.

Referring more particularly to the drawings, 7 represents a heat insulating wall surrounding the generator respectively forming or enclosing the generating chamber. This generating chamber is divided into a plurality of individual concentric combustion chambers by means of a number of circular rows of pipes or generator tubes 1, 2 and 3, each row forming in itself a continuous pipe by connecting the upper and lower ends of the vertical portions respectively to each other, the individual rows being connected with each other in a manner to be described later on. These individual rows, of which row 1 is closely adjacent to the generator wall 7, are set at their base into vertical annular

walls 55, 56 and 57; 57 forming the innermost circular wall. These annular wall portions form respectively the lower portions of the combustion chambers thus formed between the concentric rows of tubes and in the bottom of each combustion chamber are located a number of groups of burners 4, 5 and 6 respectively, which in each chamber are distributed over the entire bottom area, as is plainly visible from Figure 2. These burners are supplied with fuel from an outside source, for instance tank 15, through feeder pipes which terminate respectively in headers 12, 13 and 14 to which the individual burners are connected, control valves 50 being inserted in these connections.

The combustion air is supplied by power, as for instance from a blower 11 which feeds into annular chambers 36, 37, 38 respectively which are provided at the bottom of the combustion chambers 8, 9 and 10. From these annular chambers each combustion chamber is supplied by an air duct 39 provided in the brick wall, the air entering the combustion chambers constituting only part of the combustion air. The remainder is supplied from annular chambers 36, 37 and 38 directly into the burners. By arranging the air supply ducts which lead directly into the combustion chambers in the walls of refractory material, the latter is cooled by this air and the air in turn conveniently preheated. The remainder of the wall portion of each chamber is cooled by the generating tubes, which as Figure 1 shows, extend longitudinally through these walls. The flames develop in the chamber portions 8, 9 and 10 and thence extend upward into the combustion chambers formed between concentric rows of generating tubes so that these tubes are exposed on all sides to radiant heat. The products of combustion escape through the annular flue 16 provided at the upper portion of chamber wall 7 whence the gases escape to the flue proper as indicated in dotted lines.

For the purpose of connecting one circle of tubes with the other connecting tubes 23 and 24 are provided with flanges 18, 19, 21 and 22. The circle of tubes 1 is in communication with the circle of tubes 2 by a connecting tube 23 by the aid of tube flanges 22 and 18 and the circle of tubes 2 with the circle of tubes 3 in a similar way by a connecting tube 24 by means of flanges 21 and 19. The steam generated in the tubes escapes from the circle of tubes 3 and passes through the connecting pipe 25, joined to the tube 3 by means of the flange 20, into a consumer, not shown in the drawing, such as a steam turbine. The feed water is supplied to the tube 1 on the extreme left which is joined to the feed pipe by means of the flanges 17. The circulation cycle of the medium to be evaporated will be readily

understood from the location of the connections described above.

The arrangement of the tubes and nozzles described with reference to the embodiment illustrated may of course be varied in accordance with the space ratio and the total size selected of the steam generator plant. Instead of the concentric circles of tubes differently arranged circles of tubes may, for instance, be provided or the tubes could be arranged differently altogether. It will also be obvious to any one skilled in the art that the term "circle" with respect to the configuration of the boiler and the tube arrangement would not necessarily imply an actual round or cylindrical contour so long as the "concentric" arrangement of the tube rows remains such that these rows are exposed on both sides to a radiant heat.

The concentric arrangement of the nozzles 4, 5 and 6 is such that the heat of radiation is transmitted to the tubes as uniformly as possible and from all sides. By arranging the pipe lines in the manner illustrated and described an extraordinary large heating surface may be accommodated in a very small space and the capacity of the boiler may very considerably be increased thereby.

Various modifications and changes may be made without departing from the spirit and the scope of the invention, and I desire, therefore, that only such limitations shall be placed thereon as are imposed by the prior art.

I claim as my invention:—

1. A steam generator having a generating chamber and steam generating tubes arranged therein in concentric rows to form the walls of a plurality of concentric combustion chambers, and means for producing combustion in said chambers, said rows of tubes, except the outermost row, being exposed on all sides to radiant heat from said combustion, and pipe connections between said rows permitting the circulation of the operating medium through said tube rows.

2. A steam generator having a generating chamber and steam generating tubes arranged therein in concentric rows to form the walls of a plurality of concentric combustion chambers, and fuel nozzles directed into said concentric chambers for producing combustion therein, said rows of tubes, except the outermost row, being exposed on all sides to radiant heat from said combustion, and pipe connections between said rows permitting the circulation of the operating medium through said tube rows.

3. A steam generator having a generating chamber and steam generating tubes arranged therein in concentric rows to form the walls of a plurality of concentric combustion chambers, and fuel nozzles provided in the lower portion of said combustion chambers to distribute the total amount of combustion uniformly over all chambers and to expose

- all sides of said tube rows, except in case of the outermost row, to radiant heat from said combustion, and pipe connections between said tube rows permitting the circulation of the operating medium through said rows. 5
4. A steam generator having a generating chamber and steam generating tubes arranged therein in concentric rows to form the walls of a plurality of concentric combustion chambers, and fuel nozzles provided in the lower portion of said combustion chambers to distribute the total amount of combustion uniformly over all chambers and to expose all sides of said tube rows, except in case of the outermost row, to radiant heat from said combustion, and pipe connections between said tube rows permitting the circulation of the operating medium through said rows, the bottom of each combustion chamber being located higher than the bottom of its next adjacent inner chamber so that the bottom portions of said combustion chambers form an inverted pyramid. 10
5. A steam generator having a generating chamber and steam generating tubes arranged therein in concentric rows to form the walls of a plurality of concentric combustion chambers, and fuel nozzles provided in the lower portion of said combustion chambers to distribute the total amount of combustion uniformly over all chambers and to expose all sides of said tube rows, except in case of the outermost row, to radiant heat from said combustion, and pipe connections between said tube rows permitting the circulation of the operating medium through said rows, the bottom of each combustion chamber being located higher than the bottom of its next adjacent inner chamber so that the bottom portions of said combustion chambers form an inverted pyramid, the bottom of each combustion chamber also having walls of refractory material, said nozzles being located in said bottom portion, and combustion air ducts provided in the portion of said walls for cooling that wall portion and for preheating the combustion air, the lower portions of said tube rows extending longitudinally through another portion of said walls for cooling that wall portion. 15
6. A steam generator having a generating chamber and steam generating tubes arranged therein in concentric rows to form the walls of a plurality of concentric combustion chambers, and fuel nozzles directed into said concentric chambers for producing combustion therein, said rows of tubes, except the outermost row being exposed on all sides to radiant heat from said combustion, a gas discharge duct for removal of the products of combustion disposed laterally of the end of the chamber opposite to that at which the fuel nozzles are located. 20
